UNITED STATES PATENT OFFICE.

MODESTE LOUIS SURPRENANT, OF INDIAN LAKE, NEW YORK.

HOLDER FOR NURSING-BOTTLES.

No. 886,270.

Specification of Letters Patent.

Patented April 28, 1908.

Application filed September 14, 1907. Serial No. 392,883.

To all whom it may concern:

Be it known that I, MODESTE L. SURPRENANT, a citizen of the United States, and a resident of Indian Lake, in the county of 5 Hamilton and State of New York, have invented new and useful Improvements in Holders for Nursing-Bottles, of which the following is a full, clear, and exact description.

10 The invention has in view an improved holder for supporting and holding in convenient accessible positions while in use, an ordinary or other form of nursing bottle, whereby the child may be in easy reach of the bottle and be relieved, to an extent, of its weight, in addition to it being impossible for the bottle to be dropped to the floor and broken.

15 The invention also provides for retaining the bottle in a removed or inoperative position when it is not in use, and for preventing the accidental withdrawal of the nipple.

20 Reference is to be had to the accompanying drawings forming a part of this specification, in which similar characters of reference 25 indicate corresponding parts in both views.

Figure 1 is a perspective view of the preferred embodiment of my improved holder, showing it attached to the top rail of a bed or crib and with the bottle in position as when 30 in use; and Fig. 2 is an edge view of the construction shown in Fig. 1, showing the bottle in a removed or inoperative position.

35 The holder is in the nature of a frame, preferably of wire, and consisting of three principal members 10, 11 and 12, the member 10 serving to attach the holder in some fixed position, as to the top rail of a child's bed or cradle, as illustrated in Fig. 1. For this purpose I construct the opposite ends of 40 the member 10 with two U-shaped hooks or clips 13, the extremities of which are turned toward each other to provide fingers 14 for binding tightly against one side of the rail.

45 The intermediate portion of the member 10 is off-set at one side of the clips and pivotally or swingingly supports the member 11, the pivoted connection being effected between these two members by forming the inner extremities of the member 11 with eyes 50 15 which receive and embrace the member 10.

The member 11 is composed of two side wires which are held rigidly spaced apart near the eyes 15 by a cross-piece 16, the latter being preferably made by twisting two 55 strands of wire together and bending the extremities thereof into close embrace with the

side wires. The side wires of the opposite end of the member 11 are also bent to form eyes 17 which receive and provide guides for the side wires of the member 12, this latter member being further slidably supported from the member 11 by a cross-wire 18 which is rigidly attached to the member 12 and embraces the side wires of the member 11 at the inside of off-set portions 19 formed therein, 60 which serve as stops for limiting the sliding movement between the two members 11 and 12 in an outward direction. The cross-wire 18 at an intermediate point of its length is bent upon itself to provide a projection 20, the said projection being off-set slightly at one side, and is for the purpose of engaging the top rail of the bed, crib or other device to which the holder is attached, and retain the bottle in a removed or inoperative 70 position, as illustrated in Fig. 2.

Rigidly attached to the cross-wire 18 and extending substantially the full length thereof is a connecting-wire formed integrally with the two side wires of the member 12 and a 80 wire 21 having its ends bent outwardly and fashioned to provide clamping-jaws 22 which embrace and bind the nursing bottle about its edges a short distance from its bottom.

The side wires of the member 12, near their 85 outer ends are braced by a cross-wire 23, from which points they are turned toward each other and are provided with substantially semi-circular clamping-jaws 24 which serve to bind the nipple above the neck of the 90 bottle and prevent its accidental withdrawal when the bottle is in use.

It is apparent by reason of the pivotal connection between the members 10 and 11 and the sliding connection between the members 11 and 12, that the bottle may be swung and slidably adjusted upon its support to bring it within approximately any convenient accessible position, in addition to relieving the child of the weight of the bottle and its contents to an extent, besides preventing the bottle from being dropped to the floor and broken.

The invention as shown and described while being my preferred specific construction may nevertheless be modified within the purview of the appended claims.

Having thus described my invention, I claim as new and desire to secure by Letters Patent:

110 1. In a nursing bottle holder, a wire member having the opposite ends thereof bent to

provide clips, a second wire member consisting of side wires connected together and swingingly suspended on the intermediate portion of the first member, and a third wire member having clamping-jaws for embracing the body of the bottle and embracing the nipple about the neck of the bottle.

2. In a nursing bottle holder, a member for attaching the holder, a second member pivoted to the attaching member, and a third member slidably connected with the second member, having means for retaining the bottle.

3. In a nursing bottle holder, a member for attaching the holder, a second member pivoted to the attaching member, and a third member slidably connected with the second member, having clamping-jaws for embracing the body of the bottle and embracing the nipple about the neck of the bottle.

4. In a nursing bottle holder, a member having means for attaching it to the top rail of a crib or the like, a second member pivoted to the attaching member, a third member slidably connected with the second member, having means for retaining the bottle, and means carried by said third member for engaging said rail and holding the bottle in a removed position.

5. In a nursing bottle holder, a wire member having clamping-jaws for embracing the body of the bottle, and clamping-jaws for binding the nipple about the neck of the bottle.

6. In a nursing bottle holder, a wire member having U-shaped clips at its opposite ends with an intermediate off-set portion, a second wire member consisting of side wires spaced

apart and braced together swingingly suspended on said intermediate off-set portion of the first member, a third wire member consisting of side wires slidable in eyes formed at the extremities of the side wires of the second member, a cross-wire connected to said third wire member having eyes embracing the side wires of the second member, clamping-jaws for bindingly engaging the bottle at two points, and means carried by said third wire member for retaining the holder in inoperative position.

7. In a nursing bottle holder, a wire member having U-shaped clips at its opposite ends connected by an intermediate off-set portion, a second wire member comprising side wires spaced apart and rigidly connected together pivotally suspended on the intermediate portion of said first wire member, the side wires of said second wire member having off-set portions with eyes formed at the outer extremities thereof, a third wire member comprising side wires slidable through said eyes, a wire connected to said third wire member having eyes embracing the side wires of said second wire member at the inside of the off-set portions thereof, the said cross-wire having an off-set projection intermediate its length adapted to retain the bottle and holder in a removed position, and clamping-jaws for embracing the bottle about its body and neck.

In testimony whereof I have signed my name to this specification in the presence of two subscribing witnesses.

MODESTE LOUIS SURPRENANT.
